ELECTRIC SWITCH MECHANISMS

Gilbert Waage, Chicago, Ill.

Application May 16, 1935, Serial No. 21,725

2 Claims. (Cl. 200—1)

The main objects of this invention are to provide an improved form of electric switch mechanism, particularly of the type for controlling a plurality of different circuits; to provide an improved separator for actuating the movable contact of an electric switch; and to provide a reliable and inexpensive switch mechanism of this kind which is especially adapted for use on an electric flat iron to control the heat of the iron.

5 An illustrative embodiment of this invention is shown in the accompanying drawing, wherein:

Figure 1 is a plan view of an improved switch mechanism with both contacts open.

Figures 2, 3 and 4 are fragmentary plan views 15 showing changed positions of the rotatable separator.

Figures 5, 6, 7 and 8 are transverse sections taken on the lines 5—5, 6—6, 7—7 and 8—8 of Figures 1, 2, 3 and 4, respectively.

20 Figures 9 and 10 are enlarged sections taken on the lines 9—9 and 10—10, respectively, of Figure 1.

Figure 11 is a diagrammatic view of the switch and circuits.

25 Inasmuch as a switch mechanism embodying this invention may be used in connection with many different types of electric appliances no appliance is illustrated in the drawing.

As shown in Fig. 11, the switch may be used 30 for controlling a pair of independent circuits such as used in connection with an electric flat iron where it is desirable to obtain a "low heat", "medium heat" and "high heat". In one of the circuits, is a resistance element 1 of low resistance and in the other circuit is an element 2 of 35 higher resistance.

The improved switch mechanism embodying this invention is adapted to close either circuit independently of the other for obtaining either 40 "low" or "medium" heat and is also adapted to close both circuits for obtaining "high heat".

In the form shown, the switch comprises a conductor plate 3 secured to a supporting strap 4 by screws 5 but insulated therefrom by a sheet of 45 insulating material 6.

Mounted on the conductor plate 3 is a pair of fixed contact elements 7 and 8 adapted to cooperate with a pair of movable contact elements 9 and 10, respectively, carried by resilient conductor arms 11 and 12 which tend to urge the movable contacts into closed position.

Formed on the conductor plate 3 is a pair of offset portions 13 to which the arms 11 and 12, respectively, are secured by bolts 14, the heads 50 of which are located within channels 15 formed

by the offset portions. These bolts are insulated from the conductor plate by insulating washers 16, 17 and 18 as clearly shown in Fig. 10.

The arm 12 is connected to a conductor strip 19 wired to the resistance element 1 and the arm 11 is connected to a conductor strip 20 wired to the resistance element 2. Both resistance elements are connected in parallel to one of the supply wires 21. The other supply wire 22 is connected to a conductor strip 23 which is electrical- 10 ly connected to the conductor plate 3.

It will thus be apparent that by closing the contacts 8—10, the circuit of element 1 is closed, and by closing the contacts 7—9, the circuit of element 2 is closed. By closing both circuits 15 simultaneously both of the resistance elements are in operation.

The improved means for effecting the operation of the movable contacts comprises a rotatable separator disc 24 having a face 25 adapted to 20 slidably engage the heads 26 of bolts 27 which are mounted on the free ends of the arms 11—12. The bolts 27 are insulated from the arms 11—12 by insulation washers 28, 29 and 30 as shown in Fig. 9. The disc 24 is not a conductor. It serves 25 merely as a separator for urging the arms 11—12 away from the contacts 7—8 for opening the circuits.

The disc 24 has a pin 31 which is rotatably supported on the support 4 and which may be 30 provided with a handle 32 for manual operation.

Formed in the disc is an arcuate slot 33 which receives a pin 34 on the support 4 for limiting the rotary movement of the separator.

Also formed in the separator disc, are three 35 pockets or recesses 35, 36 and 37 for receiving the bolt heads 26 when the separator is turned so as to permit the arms 11 and 12 to close the contacts. The rims of the recesses are tapered to form cams 38 which are adapted to force the bolt 40 heads 26 out of the recesses when the separator is operated.

In order to permit the independent closing of either circuit or the simultaneous closing of both circuits, the recesses 35, 36 and 37 are preferably 45 spaced as shown.

The "off" position of the switch is shown in Figs. 1 and 11. The spacing between the recesses 35—36 is greater than the spacing between the bolt heads 26 so that, when the head 26 of arm 50 12 occupies the recess 35, as shown in Figs. 2 and 6 for closing the circuit of resistance element 1, the head of arm 11 engages the face 25 of disc 24 for holding the contact 9 retracted, and the low heat circuit is closed. Upon further 55

movement of the separator, the rim 38 of recess 35 forces the head 26 of arm 12 out of recess 35 and the head of arm 11 engages the recess 36, as shown in Figs. 3 and 7, thereby opening the "low heat" circuit and closing the "medium heat" circuit.

The spacing between recesses 36 and 37 is the same as that between the heads 26 so that, upon further rotation of the separator, both of the heads 26 may be seated in the recesses, as shown in Figs. 4 and 8, thereby closing both circuits for obtaining "high heat."

Although but one specific embodiment of this invention has been herein shown and described, it will be understood that details of the construction shown may be altered without departing from the spirit of the invention as defined by the following claims.

I claim:

20. 1. In an electric switch mechanism for controlling an electric circuit having two branches in parallel, a conductor plate in said circuit, a pair of fixed contacts on said conductor plate, a pair of resilient conductor arms secured to and insulated from said conductor plate respectively located in the branches of said circuit and carrying movable contacts normally urged by the resiliency of said arms into contact with said fixed contacts, bearing parts on corresponding ends of said arms, and a rotatable separator engaging said bearing parts to hold said movable contacts out of engagement with said fixed contacts, said separator having a plurality of recesses adapted to seat said bearing parts and so located

thereon that in one position of said separator the contacts controlling one of said branches only are closed, in a second position the contacts controlling the other of said branches only are closed, in a third position thereof the contacts controlling both of said branches are closed, and in a fourth position thereof all of said contacts are open.

2. In an electric switch mechanism for controlling an electric circuit having two branches in parallel, a flat conductor plate in said circuit, a pair of fixed contacts on said conductor plate, a pair of resilient conductor arms secured at one end thereof to and insulated from said conductor plate respectively located in the branches of said circuit and carrying movable contacts normally urged by the resiliency of said arms into contact with said fixed contacts, bearing parts on the other ends of said arms, and a rotatable separator disc mounted on an axis normal to the plane of said conductor plate, one face of which disc engages said bearing parts to hold said movable contacts out of engagement with said fixed contacts, said face formed with a plurality of recesses adapted to seat said bearing parts and so spaced around the axis of said disc that in one position of said disc the contacts controlling one of said branches only are closed, in a second position thereof the contacts controlling the other of said branches only are closed, in a third position thereof the contacts controlling both of said branches are closed, and in a fourth position thereof all of said contacts are open.

GILBERT WAAGE.
